(57) **CLAIM**

The ornamental design for a television cart, substantially as shown and described.

DESCRIPTION

FIG. 1 is a front perspective view of a television cart comprising a first embodiment of our new design;

FIG. 2 is a rear perspective view of the television cart of FIG. 1;

FIG. 3 is a front view of the television cart of FIG. 1;

FIG. 4 is a right-hand side view of the television cart of FIG. 1;

FIG. 5 is a rear view of the television cart of FIG. 1;

FIG. 6 is a left-hand side view of the television cart of FIG. 1;

FIG. 7 is a top view of the television cart of FIG. 1; and

FIG. 8 is a bottom view of the television cart of FIG. 1.

FIG. 9 is a front perspective view of a television cart comprising a second embodiment of our new design;

FIG. 10 is a rear perspective view of the television cart of FIG. 9;

FIG. 11 is a front view of the television cart of FIG. 9;

FIG. 12 is a right-hand side view of the television cart of FIG. 9;

FIG. 13 is a rear view of the television cart of FIG. 9;

FIG. 14 is a left-hand side view of the television cart of FIG. 9;

FIG. 15 is a top view of the television cart of FIG. 9; and

FIG. 16 is a bottom view of the television cart of FIG. 9.

FIG. 17 is a front perspective view of a television cart comprising a third embodiment of our new design;

FIG. 18 is a rear perspective view of the television cart of FIG. 17;

FIG. 19 is a front view of the television cart of FIG. 17;

FIG. 20 is a right-hand side view of the television cart of FIG. 17;

FIG. 21 is a rear view of the television cart of FIG. 17;

FIG. 22 is a left-hand side view of the television cart of FIG. 17;

FIG. 23 is a top view of the television cart of FIG. 17; and

FIG. 24 is a bottom view of the television cart of FIG. 17.

(Continued)

The broken lines showing portions of the unclaimed environment forms no part of the claimed design.
